US0D1022213S

(12) **United States Design Patent** (10) Patent No.: **US D1,022,213 S**
(45) Date of Patent: ** Apr. 9, 2024

(54) **WIRELESS STETHOSCOPE**

(71) Applicant: **Quanta Computer Inc.**, Taoyuan (TW)

(72) Inventors: **Barry Lam**, Taoyuan (TW);
Chia-Yuan Chang, Taoyuan (TW);
Jung-Wen Chang, Taoyuan (TW);
Kao-Yu Hsu, Taoyuan (TW)

(73) Assignee: **QUANTA COMPUTER INC.**,
Taoyuan (TW)

(**) Term: **15 Years**

(21) Appl. No.: **29/869,245**

(22) Filed: **Dec. 27, 2022**

(30) **Foreign Application Priority Data**

Nov. 21, 2022 (TW) 111305810

(51) **LOC (14) Cl.** **24-02**

(52) **U.S. Cl.**

USPC **D24/134**

(58) **Field of Classification Search**

(57) **CLAIM**

The ornamental design for a wireless stethoscope, as shown and described.

DESCRIPTION

FIG. 1 is a front perspective view of a wireless stethoscope showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines show portions of the wireless stethoscope that form no part of the claimed design.

1 Claim, 7 Drawing Sheets
